DESIGN FOR A CHAIR

Edwin J. Houghton, Ionia, Mich., assignor to
Ypsilanti Reed Furniture Company, Ionia,
Mich.

Application February 8, 1940, Serial No. 90,136

Term of patent 3½ years

To all whom it may concern:

Be it known that I, Edwin J. Houghton, a citizen of the United States, residing at Ionia, in the county of Ionia and State of Michigan, have invented a new, original, and ornamental Design for a Chair, of which the following is a specification, reference being had to the accompanying drawing, forming part thereof, in which:

Fig. 1 is a front perspective view of a chair showing my new design.

Fig. 2 is a top perspective view of a chair showing my new design. Fig. 3 is a rear perspective view of a chair showing my new design.

I claim:

The ornamental design for a chair, as shown.

EDWIN J. HOUGHTON.
